UNITED STATES PATENT OFFICE.

JOSIAH BURLEY, OF BALTIMORE, MARYLAND.

CURTAIN-FIXTURE.

SPECIFICATION forming part of Letters Patent No. 702,537, dated June 17, 1902.

Application filed August 2, 1898. Renewed November 30, 1901. Serial No. 84,245. (No model.)

To all whom it may concern:

Be it known that I, JOSIAH BURLEY, residing at Baltimore, in the State of Maryland, have invented a new and useful Curtain-Fixture, of which the following is a specification.

This invention relates to improvements in curtain-fixtures; and the object thereof is to provide a simple construction of bracket which is adjustable horizontally, so as to accommodate shade-rollers of different lengths, and also adjustable vertically to support the shade-roller horizontally and hang the shade perfectly straight at all times.

With the above object in view the invention consists in forming each of the brackets with a plate slotted vertically and provided on its inner surface with a plurality of longitudinally-extending projections or corrugations and providing a supporting-plate which is slotted longitudinally and is formed on its outer face with a plurality of longitudinally-extending projections or corrugations to coat with the corrugations of the bracket, a securing-screw passing through the vertical slot of the bracket and the longitudinal slot of the supporting-plate and engaging a nut positioned upon the inner side of said plate.

The invention further consists in the improved construction, arrangement, and combination of parts hereinafter fully described, and afterward specifically pointed out in the claim.

In order to enable others skilled in the art to which my invention most nearly appertains to make and use the same, I will now proceed to describe its construction and operation, having reference to the accompanying drawings, forming part of this specification, in which—

Figure 1 is a perspective view of a portion of a window, showing my improved curtain-fixture applied thereto and supporting a shade-roller. Fig. 2 is a vertical transverse view through the bracket and supporting-plate. Fig. 3 is a similar view showing the window-frame recessed to receive the supporting-plate. Fig. 4 is a perspective view of the securing screw and nut. Fig. 5 is a perspective view of one of the supporting-plates. Fig. 6 is a similar view of one of the brackets.

Like letters of reference mark the same

parts wherever they occur in the various figures of the drawings.

Referring to the accompanying drawings, 55 A indicates the supporting-plate, which may be either secured upon the surface of the window-frame, as illustrated in Fig. 2, or said frame may be recessed to receive it, as illustrated in Fig. 3. The supporting-plate 60 is formed at its center with a casing B, which is slotted longitudinally, as at C, and provided on its outer face with the longitudinally-extending projections or corrugations D.

E indicates one of the brackets, having the 65 plate F formed on its inner end and extending at right angles thereto, said plate being provided with the vertical slot G and on its inner face with the corrugations H, which are at right angles to said slot, adapted to coat 70 with the corrugations of the casing and prevent the slipping of the bracket when positioned upon said casing.

I is a securing-screw, having the slotted head J, said screw I passing through the vertical slot of the bracket and the longitudinally-extending slot of the casing and engaging the nut K, which is movable within said casing, as clearly illustrated in Figs. 2 and 3. The nut is substantially the same area in 80 cross-section as the cross-section of the casing, so that when it is located in the casing it can only be moved from one end to the other and without turning, so that the screw I may be tightened or loosened, as desired, 85 and by making the nut of a greater thickness than the height of the corrugations the screw can be loosened sufficiently to permit of the vertical adjustment of the bracket without disengaging the screw from the nut; but if 90 the screw should accidentally be removed from the nut it can be readily inserted, as the nut is always held so that its opening will register with the slot in the casing.

By making the supporting-plate as above 95 described it can be formed by stamping it from thin material, as the casing can be formed by forcing a portion of the base out of its normal plane and against a corrugated die, which will complete it ready for use. The 100 strain upon the walls of the casing will come in the direction of their plane and enable them to support the curtain even if made of exceedingly light weight. In addition to this

the nut within the casing will assist in supporting the outer wall of the casing, owing to its fitting between the wall and the window-casing to which the device is secured.

5 When it is desired to adjust the bracket horizontally, the screw is loosened slightly, when said adjustment may be readily effected, the corrugated surfaces of the casing and bracket permitting such movement, but preventing the bracket from becoming displaced vertically.

In order to adjust the bracket vertically, the screw must be loosened sufficiently to permit the corrugated surfaces of the casing and bracket to be disengaged, when the bracket may be moved upwardly or downwardly, as desired, so that the shade-roller may be supported in a horizontal position to keep the shade perfectly straight at all times.

15 20 From the above description it will be seen that I have produced a very simple construction of bracket-support in which the bracket may be quickly and conveniently adjusted either horizontally or vertically, as may be desired.

25 While I have illustrated and described the best means now known to me for carrying out my invention, I do not wish to be understood as restricting myself to the exact details of

construction shown and described, but hold 30 that any slight changes or variations such as might suggest themselves to the ordinary mechanic will properly fall within the limit and scope of my invention.

Having thus fully described my invention, 35 what I claim as new, and desire to secure by Letters Patent of the United States, is—

In a curtain-fixture, the combination with a perforated base provided with a casing, the outer wall of which is corrugated longitudinally on its outer face and slotted in the direction of the corrugations, a bracket which has its base corrugated transversely upon its inner face and provided with a slot at right angles to the corrugations, a nut in the casing of substantially the same area in cross-section as the cross-section of the casing and a screw passed through the slots in the bracket and the casing and engaging with said nut, said nut being of a greater thickness than 40 45 the height of the corrugations, whereby the bracket may be adjusted vertically without removing the screw from the nut.

JOSIAH BURLEY.
